his Attorney.

UNITED STATES PATENT OFFICE.

EDWARD E. PINKERTON, OF CHICAGO, ILLINOIS.

BOX.

1,143,551.

Specification of Letters Patent. Patented June 15, 1915.

Application filed March 23, 1914. Serial No. 826,659.

To all whom it may concern:

Be it known that I, EDWARD E. PINKERTON, a citizen of the United States, and a resident of the city of Chicago, county of Cook, and State of Illinois, have invented certain new and useful Improvements in Boxes, of which the following is a specification.

My invention relates to improvements in boxes, and more especially to folding boxes, and has for its object the provision of an improved construction of this character provided with means for closing the same whereby the insertion of articles therein is greatly facilitated.

A further object is to provide improved means for securing parts of a folding box together.

With these objects in view my invention consists in the combinations and arrangements of parts hereinafter described and claimed.

The invention will be best understood by reference to the accompanying drawing forming a part of this specification, and in which—

Figure 1 is a perspective view of a box embodying my invention and shown in open position, and Fig. 2, a different perspective view showing the box closed.

The preferred form of construction as illustrated in the drawing comprises a shallow folding box 3 which is provided with flaps of any usual or desired construction for closing the end 4. The opposite end of the box is provided with closing flaps 5 and 6 and a triangular cover portion 7 joined to the top of the box by a creased line 8 extending inwardly and transversely from the corner 9 to the opposite side of the box, so as to permit the cover 7 to be swung upwardly as indicated in Fig. 1. The cover 7 is provided with a flap 10 adapted to fold over the corresponding end of the box when the cover is in closed position and hold flaps 5 and 6 in close relation, said flap 10 being provided with a tongue 11 which is slit longitudinally at 12 and is adapted to be inserted in a slit 13 in the bottom of the box to lock the flap 10 and the cover 7 in closed position. The slit 12 in tongue 11 permits collapsing of said tongue to a certain degree to permit insertion in the slit 13. At its free end said cover 7 is provided with a flap 14 adapted to fit over the corresponding side of the box 3 and provided with a tongue 15

adapted to enter a slit 16 in the corresponding box side to further secure the cover 7 in position. Flap 14 is joined to flap 10 by means of a diagonally creased flap 17 which further increases the strength of the connection.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A box comprising a rectangular body and a triangular shaped cover therefor joined to the top of the box by a crease extending inwardly and transversely of the box from one corner thereof; a flap on said cover adapted to extend over the corresponding end of said box; and a tongue on said flap, there being a slit in the bottom of said box to receive said tongue, substantially as described.

2. A box comprising a rectangular body and a triangular shaped cover therefor; a flap on said cover adapted to extend over the corresponding end of said box; a tongue on said flap, there being a slit in the bottom of said box to receive said tongue; a flap on said cover adapted to extend over the corresponding side of said box; and a tongue on said last mentioned flap, there being a slit in the corresponding side of said box to receive said tongue, substantially as described.

3. A box comprising a body and a triangular shaped cover therefor joined to the top of the box by a crease extending inwardly and transversely of the box from one corner thereof; a flap on said cover adapted to extend over the corresponding end of said box; a tongue on said flap, there being a slit in the bottom of said box to receive said tongue; a flap on said cover adapted to extend over the corresponding side of said box; and a tongue on said last mentioned flap, there being a slit in the corresponding side of said box to receive said tongue, substantially as described.

4. A box comprising a rectangular body; a triangular shaped cover therefor, said

cover being hinged at one side but free on the other two sides; securing flaps on each of the other sides of said cover; and a securing tongue on each of said flaps, there being 5 corresponding interlocking slits in the box adapted to receive said tongues, substantially as described.

In testimony whereof I have signed my name to this specification in the presence of two subscribing witnesses.

EDWARD E. PINKERTON.
